UNITED STATES PATENT OFFICE.

EDWIN G. STAUDE, OF MINNEAPOLIS, MINNESOTA.

CENTRIFUGAL SPEED-REGULATOR.

1,197,309.

Specification of Letters Patent. Patented Sept. 5, 1916.

Application filed June 28, 1913. Serial No. 776,268.

To all whom it may concern:

Be it known that I, EDWIN G. STAUDE, a citizen of the United States, resident of Minneapolis, county of Hennepin, State of Minnesota, have invented certain new and useful Improvements in Centrifugal Speed-Regulators, of which the following is a specification.

The primary object of my invention is to provide a centrifugal speed regulator wherein the speed of the driven member will vary in a greater proportion than the variation in the speed of the driving member.

15 A further object is to provide an improved controlling mechanism operated by the driving member for controlling the speed of the driven member.

A further object is to provide a mechanism which will be simple and compact in construction and highly efficient in the economical transmission of power.

My invention consists generally in various constructions and combinations, all as hereinafter described and particularly pointed out in the claims.

In the accompanying drawings forming part of this specification, Figure 1 is a plan sectional view on the line $z-z$ of Fig. 4, 30 Fig. 2 is a transverse sectional view on the line $x-x$ of Fig. 1, Fig. 3 is a similar view, showing another position of the parts, Fig. 4 is a transverse sectional view on the line $y-y$ of Fig. 1, Figs. 5, 6, 7, 8, 9 and 10 35 are diagrammatic views illustrating the successive positions of the parts shown in Figs. 2 and 3 in the operation of the gearing, Fig. 11 is a plan sectional view of a modified construction.

40 In the drawing, 2 represents a frame having a housing 3 thereon to which a casing 4 is secured by suitable means, such as bolts 5. A stationary ring 6 is mounted in the housing 2 and a revolving ring 7 has bearing balls 8 on the stationary ring and encircles a hub 9 and revolves therewith on said bearing, a suitable packing 10 being interposed between said hub and the wall of the housing 3 through which said hub 45 projects. A fork 11 is formed on the outer end of said hub, terminating in a hub 12 having means for connection with a driving member, such as a collar 13. A pin 14 is centrally mounted in the hub 9 and projects outwardly beyond the same and is 50 preferably tapped into the hub 12. A pin-

ion 15 is loosely mounted on said pin between the arms 16 of the fork 11. A pin 17 is mounted in the hub 9 and has a squared end 18 to receive an arm 19 provided with teeth 20 to mesh with the pinion 15, said arm having a weighted end 21 and a set screw 22 to bear on one of the fork arms 16, being held in engagement therewith by a spring 23. On the other side of the pinion 15 is an arm 24 mounted on the outer squared end of a crank 25 which has one end journaled in the hub 9. The arm 24 has teeth meshing with the teeth of the pinion 15 to the arm 24 and both of the arms will be thrown outward by centrifugal force 75 and the crank 25 will be rocked for the purpose hereinafter described.

The inner end of the crank 25 is normally concentric with the hub 9 and has bearing rollers 26 for a ring 27 which encircles this end of the crank. A ring 28 is provided within the casing 4 and secured thereto by suitable means, such as a screw 29, and this ring is provided with a friction ring 30, 80 interiorly arranged and T-shaped in cross section. On this ring friction shoes 31 are mounted, each having a recess 32 therein decreasing in depth from one end to the other, as usual in friction shoes of this type and provided with a roller 33 and a compression spring 34, the roller being adapted to grip the friction ring and lock the shoe temporarily thereon. I prefer to provide a series of these shoes, there being four in number shown in this case, but a greater or less 85 number may be provided, as occasion may require. Each shoe is provided with an arm 35 pivoted thereon and having a hub 36 at its inner end that is journaled in bearings in the ring 27 and is free to turn 90 therein, the arms being curved slightly, as indicated in Fig. 2. Evidently, as the crank 25 revolves with the hub 9, its inner end will remain concentric with the driving member, but if said inner end is rocked by 95 the shifting of position of the arm 24 the arms 35 will be actuated, and their shoes locked on the stationary ring, as will hereinafter appear.

Adjacent to the stationary ring is a movable friction ring 37, carried preferably by a flange 38 that is formed integrally with

a bevel gear 39 loosely mounted on the shaft 40 provided with a collar 41 for connection with the driven member. The movable friction ring 37 is provided with shoes corresponding to those described and I will designate them by the same reference numeral with the addition of the exponent "a". Arms also are provided in connection with these shoes, designated by numerals 35^a having bearings at their inner end in the ring 27. Through these arms 35 and the movable ring motion is transmitted from the driving to the driven member.

Referring to Figs. 2 and 3, it will be noted 15 in Fig. 2 that the crank 25 is in its central position, concentric with the driving member, while in Fig. 3 the crank is shown rocked or rotated to a position where it is eccentric with respect to the driving member. When this movement takes place the inner end of the crank will be moved, carrying with it the ring 27, as indicated in the diagrammatic views.

Referring to Fig. 10 of these views, it will 25 be seen that the movement of the crank in the direction indicated by the arrow on the end of the crank will exert a pull on one of the arms 35 which would seem to cause a rotation of the ring 27. This rotation will 30 be resisted, however, by the arm 35^a on the opposite side of the crank and by the load-resisting rotation of the movable friction ring 37. The result is that one of the shoes 31 will become locked on the stationary ring 38 and the bearings of the arm 35 in the ring 27 will form a fulcrum upon which the shoe 31^a becoming locked on the movable ring 37 will 35 rotate this ring and the gear 39 and the driven member. The power in this case will 40 be applied between the fulcrum and the load, or through the crank to the ring 27 mounted thereon, and each arm 35 will temporarily form a bearing through its shoe 45 and the stationary ring for an arm 35^a and its shoe to rotate the movable ring, the load being shifted from one arm to another as the ring revolves. The motion in effect will 50 be a step by step one, but when the device is rapidly operated, the movement will be practically continuous and as the shoes and the bearings for the arms all operate in oil, and without the use of gears, the movement will be practically noiseless and the casing 55 being dust-proof, there will be no chance for dust and dirt to work into the bearings of the shoes and arms and interfere with the efficiency and durability of the gearing. A sleeve 42 is splined on the shaft 40 and has 60 a clutch connection at 43 for the gear 39. In Fig. 1, this sleeve is shown in neutral position, but when moved toward the right will lock the gear 39 on the shaft for direct transmission of the power. A beveled 65 gear 44 is loosely mounted on the sleeve 42

and has ball bearings 45 in the housing 4, said sleeve 42 also having a clutch connection with the gear 44 for locking it and the sleeve temporarily together. Between this gear 44 and the gear 39 is a pinion 46 for reversing the direction of movement of the gear 44 and reversing the driven member.

In Fig. 11 I have illustrated a modified construction which consists in providing a pair of each of the rings 6 and 7 and arranging them side by side in the housing to form a double bearing for the hub of a crank 47, said crank and its bearings being arranged substantially as described with reference to Fig. 1, the crank being made longer and the revolving hub and bearing rings being correspondingly enlarged to accommodate this construction. A stationary ring, similar to the one described, which I will designate by the same reference numeral, is secured to the housing and has a friction ring provided with shoes similar to those illustrated in Figs. 2 and 3. A pair of rings 27 is provided in this construction encircling the inner end of the crank and having anti-friction bearings thereon, and the arms 35 of the stationary friction ring 30 have bearings in one of the rings 27. A ring 48 has bearing balls 49 in the housing and carries friction rings 50 and 51. These rings are preferably formed integrally with the ring 48 and are relatively stationary to revolve with the ring 48. The ring 50 has friction shoes corresponding in their function to the shoes 31^a of Figs. 2 and 3; that is, these shoes will become locked on the ring 50 in substantially the same manner as described with reference to the shoes 31^a to oppose the shoes 31 on the friction ring 30 and impart a rotary movement to the ring 48. The shoes of the ring 51 operate to multiply or increase the degree of rotation of the ring 48, the construction being a substantial duplication of that shown in Fig. 1.

The operation of the device is as follows: 110 Power being applied to the driving member, the hub 9 will be revolved and when operated at a sufficient speed for centrifugal force to overcome the tension of the spring 23, the arms 19 and 24 will be thrown outward and their movement transmitted to the crank 25, one end of which is journaled in the hub 9 and revolves therewith, while the other end is concentric with the driving member. Obviously, the rocking of the 115 crank 25, resulting from the outward movement of said arms, will throw the inner end of the crank out of its concentric position and cause it to assume the positions indicated in the diagrammatic views. The load, falling on one of the arms 35^a, will resist the tendency of the opposite arm 35 to rotate the ring 27 and the bearing of said arm will form a fulcrum between which and the load the power will be applied. The move- 120

ment bodily of the ring, as indicated by dotted lines in Fig. 10, will result in the locking of the shoe 31 and the shoe 31^a, gripping the movable ring, will force it around, and through the gear mechanism described, will 5 revolve the driven member. The arms and shoes acting in pairs, will operate consecutively and a continuous revolution of the driven member will be obtained. As the 10 speed of the driving member increases, the arms will be thrown out a greater distance, the eccentricity of the inner end of the crank will be greater, and a corresponding increase in speed of the driven member will 15 follow.

I claim as my invention:—

1. The combination, with a driving member, of a driven member, a crank concentric with said driving member but capable 20 of movement to an eccentric position with respect to said member, means operatively connecting said crank with said driven member, and a governor device connected with said driven member and with said 25 crank for shifting said crank proportionately to the speed of said driving member.

2. The combination, with a driving member, of a driven member, means normally concentric with said driving member and 30 operatively connected therewith, a loosely mounted ring, a stationary friction ring, a movable friction ring operatively connected with said driven member, means for 35 rocking said concentric means to move its concentric end to an eccentric position with respect to said driving member, and means operatively connecting said stationary and movable rings with said loosely mounted ring for transmitting the power from said 40 driving member to said driven member.

3. The combination, with a driving member, of a driven member, means normally concentric with said driving member and capable of oscillation independently thereof 45 to an eccentric position with respect to said driving member, means operatively connecting said normally concentric means with said driven member, and a regulating device for rocking said normally concentric 50 means to an eccentric position and regulating the movement of said driven member proportionately to that of said driving member.

4. The combination, with a driving member and a driven member, means normally concentric with said driving member and 55 operatively connected therewith, means for moving said concentric means to an eccentric position with respect to said driving member, a stationary friction ring, a movable friction ring operatively connected with said driven member, and operative 60 connections between said stationary and movable friction rings and said concentric means.

5. The combination, with a driving member, of a driven member, a crank having one end eccentrically mounted with respect to said driving member to revolve therewith, the other end of said crank being concentric with respect to said driving member, mechanism operatively connecting the concentric end of said crank with said driven member, and means for rocking said crank to move its concentric end to an eccentric position with respect to said driving member. 70

6. The combination, with a driving member, of a driven member, a revolving hub connected with said driving member and 80 concentric therewith, a crank having one end eccentrically mounted in said hub, the other end of said crank being concentric with respect to said driving member, mechanism operatively connecting the concentric end of said crank with said driven member, and means for rocking said crank to move its concentric end to an eccentric position with respect to said driving member. 85

7. The combination, with a driving member, of a driven member, a crank having one end eccentrically mounted with respect to said driving member to revolve therewith, the other end of said crank being concentric with respect to said driving member, a ring loosely mounted on the said other end of said crank, a stationary friction ring, a movable friction ring operatively connected 90 with said driven member, means for rocking said crank to move its concentric end to an eccentric position with respect to said driving member, and means operatively connecting said stationary and movable rings with said loosely mounted ring for transmitting 100 the power from said driving member to said driven member. 95

8. The combination, with a driving member and a driven member, a crank having one end eccentrically mounted with respect 110 to said driving member to revolve therewith, the other end of said crank being normally concentric with respect to said driving member, means for rocking said crank to move its concentric end to an eccentric position, a 115 stationary friction ring, a movable friction ring operatively connected with said driven member, and operative connections between said stationary and movable friction rings and the concentric end of said crank. 120

9. The combination, with a driving member, of a driven member, a crank having one end eccentrically mounted with respect to said driving member to revolve therewith, the other end of said crank being concentric 125 with respect to said driving member, means for rocking said crank to move its concentric end to an eccentric position, a stationary friction ring, a movable friction ring operatively connected with said driven member, 130

friction shoes for said rings, and arms pivotally connecting said shoes with the concentric end of said crank.

10. The combination, with a driving member, of a driven member, a crank having one end eccentrically mounted with respect to said driving member to revolve therewith, the other end of said crank being concentric with respect to said driving member, means for rocking said crank to move its concentric end to an eccentric position with respect to said driven member; a stationary friction ring, a movable friction ring operatively connected with said driven member, friction shoes mounted on said stationary and movable rings, arms pivotally connected therewith at one end and having pivotal connections at their other end with the concentric end of said crank, the movement of said concentric end to an eccentric position during its revolution locking the shoe successively on said stationary ring and transmitting the power through said arms and shoes to said movable ring and said driven member.

11. The combination, with a driving member, of a driven member, a crank having one end eccentrically mounted with respect to said driving member to revolve therewith, the other end of said crank being normally concentric with respect to said driven member, means for rocking said crank to move its concentric end to an eccentric position, a ring loosely mounted on said eccentric end, a stationary friction ring, a movable friction ring operatively connected with said driven member, friction shoes for said rings, arms pivotally connected with said shoes at one end and journaled in

bearings at their other ends in said loosely mounted ring, the arms of said stationary ring being journaled on one side of the center of said loosely mounted ring and the arms of said movable ring being journaled on the opposite side of the center of said loosely mounted ring, whereby, when power is applied to said crank between said arms, the arms of said stationary ring will form successive fulcrums for the load applied successively to the arms of said movable ring.

12. The combination, with a driving member, of a driven member, an interposed member operatively connected with said driving member, means for moving said interposed member to an eccentric position with respect to said driving member and means having a fulcrum between said interposed member and said driven member for operating the latter.

13. The combination, with a driving member and a driven member, of an oscillating member normally concentric with said driving member and connected therewith, means for oscillating said normally concentric member to an eccentric position with respect to said driving member, a stationary friction member, a movable friction member operatively connected with said driven member, and operative connections between said movable and stationary members and said oscillating member.

In witness whereof, I have hereunto set my hand this 20th day of June, 1913.

EDWIN G. STAUDE.
